UNITED STATES PATENT OFFICE.

EDGAR D. DICKINSON, OF SCHENECTADY, NEW YORK, ASSIGNOR TO GENERAL ELECTRIC COMPANY, A CORPORATION OF NEW YORK.

TURBINE INSTALLATION FOR SHIPS.

1,328,497.

Specification of Letters Patent. Patented Jan. 20, 1920.

Application filed June 14, 1918. Serial No. 239,931.

To all whom it may concern:

Be it known that I, EDGAR D. DICKINSON, a subject of the King of Great Britain, residing at Schenectady, in the county of 5 Schenectady, State of New York, have invented certain new and useful Improvements in Turbine Installations for Ships, of which the following is a specification.

The present invention relates to turbine 10 installations for ships, and particularly to installations comprising a main turbine and a cruising turbine with a coupling between them, and so arranged that when operating at high speeds the coupling may be disconnected, the main turbine alone being used, while when operating at cruising speeds the 15 coupling is connected and the two turbines are operated in series, the elastic fluid passing first through the cruising turbine and then through the main turbine. Such 20 installations also comprise in general a reversing turbine element, which may be a reversing wheel or wheels built into the casing of one of the turbines, or a separate turbine.

With such installations, it is very desirable 25 that the controlling members for the turbine valves and the coupling, which controlling members may be hand operated levers, for example, be so arranged that it is not possible for the operator to make a mistake in maneuvering the ship, and the 30 primary object of the present invention is to provide an improved interlocking arrangement for such controlling members which 35 will insure this result.

Other objects of my invention will be apparent 40 from the following description and for a consideration of what I believe to be novel and my invention, attention is directed 45 to the accompanying description and the claims appended thereto.

In the drawings, Figure 1 is a side elevation 50 of a ship's turbine installation embodying my invention; Fig. 2 is a plan view thereof; Fig. 3 is a side elevation partly broken away, and Fig. 4 is a top plan view 55 of a part of a leverage mechanism; Fig. 5 is a diagrammatic view of an electric switch mechanism; Fig. 6 is a side elevation with certain parts broken away; Fig. 7 an 60 end view, and Fig. 8 a top plan view, of an interlocking mechanism used in the system; Fig. 9 is a side elevation partly in section 65 and Fig. 10 an end view of a valve mechanism; Fig. 11 is a section taken on line 10--

10 Fig. 10; Fig. 12 is a sectional view of another valve mechanism, and Fig. 12^a is a section taken on line *a*—*a* Fig. 12.

In the present instance my invention is shown and described in connection with a 60 turbine installation as disclosed in the application of William L. R. Emmet, Serial Number 84489, filed March 15, 1916, but it will be understood, of course, that the invention is not necessarily limited thereto. 65 It will also be understood that the invention is not necessarily limited to use with elastic fluid turbines as other forms of prime mover may be used. However, the principal application is in connection with turbines and 70 as a matter of convenience the invention is described in such connection.

Referring to the drawing, 13 indicates a 75 main turbine of suitable type, having an ahead section to which elastic fluid is admitted by a conduit 13^a which leads to the first stage, and a reversing section to which elastic fluid is admitted by a conduit 14. Hereinafter the ahead section is referred to 80 as the main turbine or main ahead turbine and the reversing section is referred to as the reversing turbine and it will be understood that by these terms I mean either wholly separate ahead and reversing turbines or ahead and reversing turbines built 85 into a common casing. Elastic fluid may also be admitted to an intermediate stage of the ahead turbine by a conduit 15 in case of overloads. The conduits 13^a, 14 and 15 connect with a valve casing 16 in which 90 are three valves, an ahead valve 17, an astern valve 18, and an overload valve 19. Elastic fluid is conveyed to a steam chest in valve casing 16 by a conduit 20 and the passage of elastic fluid from such steam 95 chest to any one of the conduits 13^a, 14 and 15 is controlled by valves 17, 18 and 19 respectively. The valves 17 and 19 are in series so that valve 17 must be open before 100 elastic fluid can be admitted through valve 19 to the intermediate stage of the main turbine. 21 indicates the exhaust opening of turbine 13, and 22 the shaft. Turbine 13 is shown as connected to drive a propeller shaft 23 through a suitable gearing 105 24. 25 indicates a cruising turbine the shaft of which is adapted to be connected to the shaft of the main turbine 13 by a suitable coupling device or mechanism indicated generally by reference numeral 26. This cou- 110

pling device or mechanism may be of any suitable character. In the present instance it is indicated as being of the type disclosed in the aforementioned application of W. L. 5 R. Emmet, wherein is provided an induction generator having one of its elements driven by the main turbine 13 and the other by the cruising turbine 25, and a synchronous motor having one of its elements stationary and the other mounted on the shaft 10 of the main turbine with the armature elements of the generator and motor electrically connected together to produce opposite directions of phase rotation. In the 15 drawing A indicates the induction generator and B the synchronous motor. 27 is an electric switch by means of which the generator A is connected to line wires 28. It is of a suitable type adapted to be opened 20 and closed manually by handles 27^a. It is also arranged to be tripped and opened automatically by pulling down on a rod 29 or by closing an electric circuit through conductors 30 which are connected to an electro-magnetically operated tripping device 25 for the switch. The switch 27 and a suitable arrangement for automatically tripping it is illustrated diagrammatically in Fig. 5. A double break switch is shown which is 30 biased by gravity to an open position and is held closed by a catch lever 28^a. Whenever rod 29 is pulled downward the catch 28^a will be moved to release the switch 27 and permit it to open, and as will be clear, the 35 switch cannot be again held closed by the catch until the catch is released by rod 29. The catch is also released when an electric circuit is closed through conductors 30 which are shown as connected to an electro-magnet 30^a located below latch 28^a. The 40 arrangement for closing this circuit is explained hereinafter.

Elastic fluid is admitted to cruising turbine 25 by a conduit 31 in which is a controlling valve 32, and exhausts therefrom into a conduit 33 which leads to the admission end of the main turbine 13. In conduit 33 is a stop valve 33^a and a non-return valve 33^b. By this means the main turbine 45 13 and cruising turbine 25 may be connected in series when the ship is to be operated at cruising speeds. Elastic fluid is supplied to conduits 20 and 31 by a main conduit 34 which leads from a suitable source of supply, such as a boiler. In conduit 34 is a 50 boiler stop valve 35.

The valves 17, 18, 19 and 32 are the operating or maneuvering valves for the installation, that is, they are the manually operated valves by which the turbines are controlled at will and I provide an arrangement whereby valves 17, 18 and 32 are operated from a set of levers all located at the same point and interlocked with each 55 other so as to insure the correct operation

of the valves for any running condition. If desired, an operating lever for the overload valve 19 may be provided at this same point also. However, in the present instance, the overload valve 19 is in series with the ahead 70 valve 17, so that when the ahead valve is closed the supply of elastic fluid is shut off from the overload conduit 15, and because of this arrangement, and also the fact that the overload valve is used in general only 75 occasionally I do not connect it to be operated from the interlocking mechanism.

The valves 17 and 18 may be of any suitable type and they are provided with operating arms 36 and 37, to which are fastened 80 rods 38 and 39 leading to bell crank levers 40 and 41 (see Figs. 1 and 2). Bell crank lever 40 is connected by a rod 42 to an arm 43 fixed on one end of a pivotally mounted shaft 44. On the other end of shaft 44 is 85 an arm 45 connected by a rod 46 to a hand lever 47. Bell crank lever 41 is connected by a rod 48 to an arm 49 fixed on one end of a pivotally mounted shaft 50. On the other end of shaft 50 is an arm 51 which is 90 connected by a rod 52 to a hand lever 53. Valve 32 has an operating arm 54 (Fig. 10) which is connected by a rod 55 to a lever arm 56 fixed on the end of a pivotally mounted shaft 57. On the opposite end of 95 shaft 57 is an arm 58 which is connected by a rod 59 to a hand lever 60.

Hand levers 47, 53 and 60 are pivotally mounted on a shaft 61 (Figs. 6, 7 and 8) and are held in spaced relation to each 100 other by spacing sleeves 62. Shaft 61 is supported at its two ends in two rectangular side members 63 and 64 which are held in spaced relation to each other by end braces 65 and tie rods 66. Side members 63 and 64, 105 end braces 65 and tie rods 66 form the framework of an interlocking mechanism for levers 47, 53 and 60. Each of levers 47, 53 and 60 comprises two flat strips designated 110 47^a, 53^a and 60^a, which at their lower ends are fastened to pivoted bars 47^b, 53^b and 60^b respectively and at their upper ends to handles 47^c, 53^c and 60^c respectively. The flat strips 47^a, 53^a and 60^a straddle segments 67, 115 68 and 69 respectively and are arranged to be squeezed or clamped against such segments by tightening the nuts 70 on the ends of bolts 71. The nuts 70 are provided with handles 72 for this purpose and by this means the levers 47, 53 and 60 can be 120 clamped in any desired positions. The segments 67, 68 and 69 also serve to guide the levers 47, 53 and 60 during their movements. Pivoted to end braces 65 and between levers 47 and 53 is a locking member comprising a 125 rectangular frame 73 carrying a flat locking plate 74 on its upper edge. The frame 73 is pivoted at its two lower corners on a shaft 75 and is adapted to move on such pivots crosswise of the frame work of the interlock- 130

ing mechanism. Similarly pivoted between levers 47 and 60 is a second locking member comprising a frame 76 carrying a flat locking plate 77 on its upper edge. The locking plates 74 and 77 are of such a width that when in their central positions, as best shown in Fig. 8, they overlap levers 47, 53 and 60. When the levers 47, 53 and 60 are in the positions shown in Fig. 8, the valves which they control are closed. This may be termed their forward positions and when in such positions they are opposite notches 78 in locking plates 74 and 77. Because of these notches 78, the locking plates 74 and 77 may be spread apart to permit lever 47 to move between them or they may be pushed to one side or the other to permit either lever 53 or 60 to be moved. The arrangement is such that when lever 47, 53 or 60 is moved, the lever itself moves the locking plates 74 and 77, the frames 73 and 76 which carry locking plates 74 and 77 oscillating on their pivots. On frames 73 and 76 are projecting studs 79 which engage each other to cause frames 73 and 76 to move together. With this arrangement it will be clear that when lever 47 is thrown backward from its forward position to open the ahead valve 17 of main turbine 13 it will spread locking plates 74 and 77 apart thus locking levers 53 and 60 against movement, that when lever 53 is thrown backward from its forward position to open astern valve 18 it will force both locking plates 74 and 77 to one side thus locking levers 47 and 60 against movement, and that when lever 60 is thrown backward from its forward position to open cruising valve 32 it will force both locking plates 74 and 77 to the other side thus locking levers 47 and 53 against movement. In any event but one of the levers 47, 53 and 60 can be thrown at a time or, in other words, only one of the valves 17, 18 and 32 can be open at a time, and before any one of them can be opened, the others must be closed.

Whenever either the main ahead valve 17 or the astern valve 18 is open the cruising valve 32 must be closed and at such times it is also always desirable that the clutch mechanism between the cruising turbine shaft and the main turbine shaft be uncoupled or rendered inoperative, and to accomplish this I connect a controlling means for such clutch mechanism to the valve operating mechanism of valves 17 and 18 so that whenever either of these valves is opened, the clutch mechanism will be uncoupled or rendered inoperative. If it is closed it will be automatically opened or if already opened it will not be possible to close it. In the present instance the latch releasing rod 29, already referred to, is connected to one end of a lever 80 which is pivoted on a shaft 81 carried on a standard 82 (see Figs. 3 and 4). The lever 80 is normally pressed

upward and away from catch 28^a by a spring 83 located between a projection 84 on lever 80 and standard 82. The end of lever 80 remote from rod 29 is in the form of a flat plate 85 and the under surface of such flat plate is adapted to be engaged and lifted by either of two separate levers 86 and 87 which are pivoted at one end on shaft 81 and have their other ends connected to separate toggles 88 and 89. Whenever either of the toggles 88 or 89 is straightened, lever 86 or 87 will be lifted thus turning lever 80 and pulling down on rod 29 which in turn raises catch 28^a from engagement with switch 27. If the switch 27 is closed as soon as the catch 28^a is lifted it will automatically open and it cannot again be closed until catch 28^a is released. Of course it will be understood that this catch arrangement is only illustrative and that the showing is diagrammatic. In actual practice any approved structure for accomplishing the result desired may be utilized. Toggles 88 and 89 are connected by rods 90 and 91 to arms 92 and 93 on shafts 44 and 50 respectively. Either toggle 88 or 89 will thus be straightened whenever hand lever 47 or 60 is thrown to open valve 17 or 18.

The operation of the arrangement so far described is as follows:

If it is desired to operate the ship at cruising speed the hand lever 60 is thrown from its forward position backward to open cruising valve 32 and admit elastic fluid to the cruising turbine 25. At the same time the switch 27 is closed by means of handles 27^a to render operative the clutch mechanism 26. The hand lever 60 is moved to such a position that valve 32 is opened sufficiently to admit an amount of elastic fluid to give the desired speed. The hand levers 47 and 53 must of course be in their forward positions, which means that valves 17 and 18 are closed, before hand lever 60 can be moved, and as soon as hand lever 60 is moved to open cruising valve 32 the interlocking plates 77 and 74 are pushed to one side so as to lock hand levers 47 and 53 against movement. The exhaust steam from cruising turbine 25 will pass by way of conduit 33 to the main turbine 13, the stop valve 33^a of course being open. Such operation of a cruising turbine and a main turbine in series is well known and understood in the art of ship propulsion. In the present instance the arrangement for driving the propeller, as shown in Figs. 1 and 2, is one-half of the installation for a ship having two propellers, the arrangement for the other propeller being a duplicate of the one shown. 94 indicates a branch conduit leading from conduit 33 to a conduit similar to conduit 33 and appurtenant to the other half of the installation. If desired elastic fluid from the cruising turbine 25 of one

propeller may be in part or entirely passed to the main turbine of the other propeller by way of conduit 94.

If now it is desired to operate the installation at full speed ahead the hand lever 60 is first pulled forward to close cruising valve 32 and the hand lever 47 is then moved to open the ahead valve 17. At the same time it forces apart the interlocking plates 74 and 77 and locks hand levers 53 and 60 in inoperative position. Also if the operator has neglected to open the switch 27 manually when shutting off the cruising valve 32 then when hand lever 47 is moved it will 10 pull rod 90 and straighten toggle 88 thus pulling down rod 29 and releasing the catch 28^a which will permit the switch 27 to automatically open. It will also be noted that so long now as the hand lever 47 is in 15 position to hold ahead valve 17 open the catch 28^a will be held in such a position that the switch 27 cannot be latched shut. The installation can then be operated at full 20 speed ahead, the hand lever 47 being set to such a position that it admits a quantity of 25 steam sufficient to give the desired speed. In case a still higher speed is desired, that is a speed corresponding to an overload on the main turbine 13, the valve 19 is manually 30 opened thereby admitting elastic fluid through conduit 15 directly to an intermediate stage of the main turbine 13. As already stated the overload valve 19 is in series with the valve 17 so that elastic fluid 35 can be admitted through it to the turbine 13 only when the ahead valve 17 is already open. Due to this arrangement the admission of elastic fluid through the overload valve 19 to the turbine is in reality under 40 control of the hand lever 47 which is interlocked with the levers 53 and 60.

If now it is desired to reverse the ship the hand lever 47 is brought to its forward position to close the ahead valve 17 and the 45 astern lever 53 is moved to open reverse valve 18 to admit elastic fluid by way of conduit 14 to the reversing turbine, *i. e.* the reversing section of the main turbine. When astern lever 53 is moved the interlocking plates 74 and 77 are pushed to one side thus locking levers 47 and 60 in inoperative position. At the same time the rod 91 is pulled to straighten toggle 89 and pull down the catch 28^a of switch 27 so that 50 switch 27 be closed it will be automatically released or, assuming that it is already open the catch will be held in such a position that the switch cannot be latched shut.

60 It will be noted that with this arrangement the operator cannot make a mistake in the operation of his controlling levers or in the manipulation of the switch 27. But one of the operating levers can be moved at a 65 time and the switch 27 can only be latched

shut when the levers 47 and 53 which control the ahead and astern valves of the main turbine 13 are in inoperative position so that valves 17 and 18 are closed.

In an installation of this character it is 70 desirable to utilize in connection with the cruising turbine a speed controlled valve mechanism which will regulate the speed of the cruising turbine within certain limits. To this end I provide in conduit 31 at a 75 point between the cruising valve 32 and the inlet to the turbine a suitable controlling valve 95 having an operating lever 96 (see Figs. 9, 10 and 11) which is connected by rod 97 to the piston of fluid actuated motor 98. 80 The pilot valve 99 of fluid actuated motor 98 has its stem connected to a governor arm 100 which in turn is connected to a spindle 101 of a speed governor. This speed governor may be of any desired type and 85 operates in the usual manner to move the spindle 101 back and forth thereby turning governor arm 100 and moving the pilot valve 99 to cause the fluid actuated motor 98 to operate. The operation of a fluid actuated 90 motor as shown in section in Fig. 11, is of course well understood and needs no detailed description. The actuating fluid is admitted to it through a suitable conduit connected to the opening 102 and the discharge from the 95 motor is led away through conduit 103. By this arrangement the amount of elastic fluid which can be admitted by the cruising valve 32 is limited by the governor controlled valve 95 so that in no case can sufficient elastic fluid be admitted to cause an undue overspeeding of the cruising turbine. In actual practice the speed governor will preferably be set so that it has no practical effect on the speed of the cruising turbine 25 until the 100 turbine has reached a speed somewhat above normal, for example, three per cent. After such speed is reached then each position of the governor determines a definite position of the piston of the fluid actuated motor 98 110 and consequently the amount of elastic fluid passing through the controlling valve 95. The governor is designed to have a suitable range; for example, it may have a regulation of about four per cent., in which case 115 the controlling valve 95 would be entirely closed at a speed seven per cent. above normal, if it is assumed that the governor comes into play at a speed three per cent. above normal as referred to above. It will be understood of course that the figures given are only by way of example and are not to be taken as limitations of my invention.

Since any elastic fluid turbine can accelerate at a very rapid rate and since increase 125 of speed may not be easily perceptible, it is always desirable that all turbines be equipped with an emergency governing mechanism which will operate to quickly shut off the supply of elastic fluid thereto 130

in case of excess speed. The emergency governing mechanism for the cruising turbine comprises a quick closing valve mechanism 105 (Figs. 1 and 2) which may be of any suitable type. In the present instance a valve mechanism is indicated which is adapted to be tripped by a downward pull on a link 106. The detail structure of valve mechanism 105 is not illustrated as it forms no part of the present invention. Link 106 is connected to the stem 107 of a piston 108 located in a cylinder 109. The upper end of cylinder 109 is connected to conduit 31 by a pipe 110 and the lower end is connected by a pipe 111 to a region of lower pressure, for example to atmosphere. In pipe 111 is a relief valve mechanism 112 (see Fig. 12) comprising a casing 113 having a seat 114 upon which is seated a valve 115. Valve 115 is normally held seated by a spring 116 and by the unbalanced pressure on a piston 117 which is formed integral with valve 115 and slides in a cylinder 118. Leading from cylinder 118 is a relief conduit 119 normally closed by a plunger 120. When emergency valve mechanism 105 is open, high pressure elastic fluid passes by way of pipe 110 to the upper end of cylinder 109 and leaks past piston 108 and through pipe 111 to valve casing 113. Here it leaks past piston 117 and, providing conduit 119 is closed by plunger 120, builds up a pressure above piston 117 and hence serves to hold valve 115 to its seat. With valve 115 closed the pressure is maintained in pipe 111 and since piston 108 is unbalanced by the area of its stem 107, such piston will be maintained in its upper position as shown in Fig. 1 so long as valve 115 remains seated. Valve 115 will be automatically unseated whenever plunger 120 is raised to open conduit 119 thus relieving the pressure above piston 117 and when valve 115 is opened the pressure below piston 108 in cylinder 109 is immediately relieved through pipe 111 with the result that piston 108 is forced downward, pulling on link 106 and tripping the quick closing valve mechanism 105, permitting it to close. The plunger 120 is connected to an arm 121 pivoted at one end on a bracket 122 and having its other end connected by a link 123 to a lever 124. Lever 124 is pivoted on a standard 125 and is provided with an operating handle 126 which may be used for resetting it, and for tripping the emergency valve mechanism by hand. Lever 124 is normally held in the position shown in Fig. 12, that is a position to maintain conduit 119 closed by plunger 120, by a spring pressed trip rod 127.

60 The connection between the trip rod 127 and lever 124 is best shown in Fig. 12. Lever 124 comprises two flat strips between which the flattened upper end of rod 127 projects. In the end of rod 127 is a longitudinally extending slot 128, through which

passes a bolt 129. Bolt 129 projects through openings in the two flat strips of lever 124 and also through openings in two ears 130 carried by a collar 131 which surrounds the end of rod 127 just below lever 124. Collar 131 is thus rigidly connected to lever 124 while rod 127 is connected thereto by a lost motion connection. Rod 127 is provided with a threaded section 132 upon which is a flanged nut 133 and lock nut 134, and located between nut 133 and collar 131 is a spring 134 which serves to hold lever 124 in such a position that bolt 129 is at the top of slot 128. The lower end of rod 127 is normally supported on a trip finger 135 pivoted on a pin 135, and pressed toward the end of rod 127 by a spring 136. Rod 127 is pressed downward by a spring 137 which engages at one end a stationary support 138 and at the other end a collar 139 fixed on rod 127. Whenever trip finger 135 is moved from under rod 127 the spring 137 will press it downward thus pulling down on lever 124 and raising plunger 120 thereby causing the emergency valve 105 to close as already explained. The downward movement of rod 127 is limited by its end striking finger 135. To reset the trip mechanism the rod 127 is lifted and the plunger 120 restored to its original position by raising the handle 126, the trip finger 135 automatically moving under the end of rod 127. Owing to the lost motion connection between rod 127 and lever 124, the lever can be moved by hand to raise the plunger 120 by moving the handle 126 downward, the bolt 129 moving down in slot 128. The emergency valve mechanism 105 can thus be tripped by hand.

65 Trip finger 135 may be moved from under rod 127 by any suitable speed responsive device, or any other device which responds to an abnormal condition of operation. In the present instance a well known form of speed responsive device is shown comprising a plunger 141 which slides in guide bushings 142 and 143 arranged in an opening in a shaft indicated at 144. In the present instance this is the shaft of the cruising turbine 25. The plunger 141 is held in the opening against centrifugal force by a spring 145 which surrounds plunger 141 and engages bushing 142 at one end and a collar 146 on plunger 141 at the other end. Spring 145 is so adjusted that when a certain speed is reached the plunger 141 will be thrown out by centrifugal force to engage trip finger 135 as is well understood.

70 Whenever the emergency valve mechanism 105 for the cruising turbine is closed it is also desirable that the clutch mechanism be rendered inoperative, and it is for this purpose that the switch 27 is arranged to be released magnetically by electro-magnet 30 already referred to. The circuit 30 for magnet 30 leads to a pair of contacts 147 (Fig. 130

12) which are bridged by a plate 148 carried by a lever 149 whenever lever 124 is actuated to trip the emergency valve 105. For this purpose lever 149 may be connected to lever 124 by a rod 150.

The emergency valve mechanism for the main turbine 13 is similar to that just described for the cruising turbine 25 except that it does not embody the arrangement for rendering the clutch mechanism inoperative. Referring to Fig. 1, 151 indicates the valve mechanism, 152 the cylinder corresponding to cylinder 109, 153 and 154 the two pipes which connect cylinder 152 to conduit 20 and 15 to a region of lower pressure respectively, and 155 the mechanism corresponding to that shown in Figs. 12 and 12^a and already described. The operation of the emergency valve mechanism for main turbine 13 will be understood from description already given in connection with that for the cruising turbine 25.

In accordance with the provisions of the patent statutes, I have described the principle of operation of my invention, together with the apparatus which I now consider to represent the best embodiment thereof; but I desire to have it understood that the apparatus shown is only illustrative and that 30 the invention can be carried out by other means.

What I claim as new and desire to secure by Letters Patent of the United States, is:—

1. In combination, a main turbine, a cruising turbine, electrical clutch mechanism for connecting them together, a switch for said clutch mechanism, controlling levers for said turbines, interlocking mechanism for said levers, and means associated with said 40 levers for controlling said switch.

2. In combination, a main turbine, a cruising turbine, electrical clutch mechanism for connecting their shafts together, a switch for said clutch mechanism, valves for said 45 turbines, means for operating said valves, and means for opening said switch to render the clutch mechanism inoperative when the valve for the main turbine is open.

3. In combination, a main turbine, a cruising turbine, a reversing turbine, electrical clutch mechanism for connecting the cruising turbine to the main turbine, a switch for said clutch mechanism, controlling means for said turbines, interlocking mechanism 55 for said controlling means, and controlling means for said switch associated with the turbine controlling means.

4. In combination, a main turbine, a cruising turbine, clutch mechanism for connecting them together, an emergency valve mechanism for the cruising turbine, and means for rendering the clutch mechanism inoperative when said emergency valve mechanism is tripped.

5. In combination, a main turbine, a cruis-

ing turbine, a reversing turbine, emergency valve mechanisms for said turbines, a clutch mechanism for connecting the cruising turbine to the main turbine, and means rendering said clutch inoperative when the emergency valve mechanism for the cruising turbine is tripped.

6. In combination, a main turbine, a cruising turbine, clutch mechanism for connecting them together, controlling levers for said turbines, interlocking means for the controlling levers, an emergency valve mechanism for the cruising turbine, and means for rendering said clutch mechanism inoperative when said emergency valve mechanism is tripped.

7. In combination, a main turbine, a cruising turbine, clutch mechanism for connecting them together, controlling levers for said turbines, interlocking means for the controlling levers, an emergency valve mechanism for the cruising turbine, and means for rendering said clutch mechanism inoperative when said emergency valve mechanism is tripped or when the controlling lever for 90 the main turbine is operated.

8. In combination, a main turbine, a cruising turbine, a reversing turbine, controlling valves for said turbines, operating levers for said valves, interlocking means for said levers whereby only one of said valves can be opened at a time, emergency valve mechanism for said turbines, a clutch mechanism for connecting the cruising turbine to the main turbine, and means rendering said clutch mechanism inoperative whenever either the main turbine controlling valve or the reversing turbine controlling valve is open or when the emergency valve mechanism for the cruising turbine is tripped.

9. In combination, a main turbine, a cruising turbine, an electrical clutch mechanism for connecting them together, controlling means for said turbines, an electric switch for said clutch mechanism, and means associated with the controlling means for the main turbine for controlling said electric switch.

10. In combination, a main turbine, a cruising turbine, an electrical clutch mechanism for connecting them together, controlling valves for said turbines, levers for throwing said valves, an electric switch for said clutch mechanism, and means connecting it to the lever for the main turbine valve 120 whereby whenever such lever is moved to open the valve for the main turbine, such switch will be opened.

11. In combination, a main turbine, a cruising turbine, an electrical clutch mechanism for connecting them together, controlling valves for said turbines, levers for throwing said valves, interlocking mechanism for said levers, an electric switch for said clutch mechanism, and means connect-

ing it to the lever for the main turbine valve whereby whenever such clutch is moved to open the valve for the main turbine, such switch will be opened.

5. 12. In combination, a main turbine, a reversing turbine, a cruising turbine, electrical clutch mechanisms for connecting the main turbine and the cruising turbine together, controlling valves for said turbines, levers for throwing said valves, an electric switch for said clutch mechanism, and means connecting said switch to the levers for the main turbine and the reversing turbine valves.
10. 13. In combination, a main turbine, a reversing turbine, a cruising turbine, electrical clutch mechanism for connecting the main turbine and the cruising turbine together, controlling valves for said turbines, levers for throwing said valves, interlocking mechanism for said levers, an electric switch for

said clutch mechanism, and means connecting said switch to the levers for the main turbine and reversing turbine valves.

14. In combination, a main turbine, a 25
cruising turbine, a reversing turbine, an
electrical clutch for connecting the main tur-
bine to the cruising turbine, a switch for
controlling said clutch, controlling valves
for said turbines, operating means for said 30
valves, an emergency valve mechanism for
the cruising turbine, and means for open-
ing said switch whenever the operating
means for the main turbine or the reversing
turbine is actuated to open the controlling 35
valve for the main turbine or the reversing
turbine or whenever said emergency valve
mechanism is tripped.

In witness whereof, I have hereunto set
my hand this 12th day of June, 1918.

EDGAR D. DICKINSON.
